UNITED STATES PATENT OFFICE.

BENNIE U. GAAR, OF SPOKANE, WASHINGTON, ASSIGNOR OF ONE-HALF TO ARTHUR R. LOCKWOOD, OF SPOKANE, WASHINGTON.

DUST-COLLECTOR.

1,177,506.

Specification of Letters Patent. Patented Mar. 28, 1916.

Application filed May 21, 1915. Serial No. 29,656.

To all whom it may concern:

Be it known that I, BENNIE U. GAAR, a citizen of the United States, residing at Spokane, in the county of Spokane and 5 State of Washington, have invented new and useful Improvements in Dust-Collectors, of which the following is a specification.

This invention relates to that class of devices which are generally known as dust collectors, and it has for its object to produce 10 a device of this class which will be especially adapted to be applied to and used in connection with an ordinary grain separator or threshing machine of well known 15 construction.

A further object of the invention is to produce a device of the class described which may be conveniently installed upon or applied to an ordinary threshing machine for 20 the purpose of removing dust and gases arising during the operation of the machine, thereby eliminating the danger of fire from this source, it being well known that destructive fires have been frequently caused 25 by the explosive dust and gaseous contents of threshing machines being ignited by sparks caused by the teeth of the cylinder striking hard substances accidentally introduced into the machine and from other 30 causes.

A further object of the invention is to produce a dust and gas collector which while removing the dangerous and obnoxious dust and gases from the interior of the 35 machine will not interfere with the passage of small particles of straw, chaff and the like.

With these and other ends in view which will readily appear as the nature of the 40 invention is better understood, the same consists in the improved construction and novel arrangement and combination of parts which will be hereinafter fully described and particularly pointed out in the claims.

45 In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing.—Figure 1 is an end view 50 of a fan used in connection with the invention. Fig. 2 is a sectional detail view taken

on the line 2—2 in Fig. 1. Fig. 3 is a perspective detail view showing the screen casting with parts broken away. Fig. 4 is a sectional view taken on the line 4—4 in Fig. 5 of the fan casing or housing and related 60 parts. Fig. 5 is a sectional view taken on the line 5—5 in Fig. 4. Fig. 6 is a perspective detail view of the gate or valve removed from the housing. Fig. 7 is a diagrammatic view illustrating the application of the invention to a threshing machine.

Corresponding parts in the several figures are denoted by like characters of reference.

The casing or housing 15 of the improved device is preferably of rectangular shape, 75 the walls thereof being provided adjacent to their lower edges with flange members 16 of L-shaped cross section for the passage of bolts or other devices whereby it may be mounted on the deck 17 of an ordinary 75 threshing machine. The housing is provided with an upwardly tapered top portion 18 having an opening 19 communicating with a discharge duct 20 which has been shown in the form of an elbow and which may 80 communicate with the outer air, although, when desired, a receptacle may be connected therewith to receive material discharged therethrough. The casing or housing has a 85 transverse partition 21 extending downwardly from the top portion 18 and terminating some distance above the lower edges of the side walls so as to produce an opening 22, it being understood that the bottom 90 of the housing may be formed by the deck 90 of the threshing machine on which it is mounted. Slidably engaging the partition 21 is a gate or valve 23 which is equipped with racks 24 engaged by pinions 25 mounted on a shaft 26 which is supported for rotation in the walls of the casing, said shaft having a hand wheel 26', whereby it may 95 be rotated to effect adjustment of the gate or valve for the purpose of varying the area 100 of the opening 22.

The casing is divided by the partition 21 into two compartments A, B, the latter of which communicates with the discharge duct 20, the partition being so arranged as to obstruct communication between the compartment A and the discharge duct except through the opening 22 and the chamber B. The latter chamber or compartment contains a fan 27 which is mounted on a shaft 28 that projects through the wall of the housing, 110

suitable supports or pedestals 29 being provided to afford bearings for said shaft which is also provided with a driving pulley 30 to receive motion through the medium of a belt 5 or band 31 from a source of power such as a moving part of the threshing machine to which the device is applied.

The compartment A is provided with a plurality of inlets 32 which may be formed 10 either in the walls of the housing bounding said compartment or in the deck of the threshing machine on which the housing is mounted, said openings being preferably equipped with sleeves 33 for the reception 15 of slidable ducts 34, each carrying a screen casing C, one of said casings being shown in detail in Fig. 3 of the drawings. The ducts 34 extend through the deck of the threshing machine so that the casings C will be supported below the deck and within the casing 20 of the threshing machine. Each of the screen casings is composed of an upwardly bulged rectangular top member 35 which for convenience will be called the dome, said 25 top member having hingedly connected with the front edge thereof a screen 36 made preferably of slotted sheet metal, although suitable foraminous material of any kind may be employed. The side and rear edges 30 of the screen are connected with the side and rear edges of the dome by wall members 37 of flexible material, such as textile material, leather or the like, which is capable of collapsing, accordion-wise, to permit the rear 35 edge of the screen to swing upwardly in the direction of the rear edge of the hood. The screen which faces toward the front end of the threshing machine will thus be supported in a downwardly and rearwardly inclined 40 position, and its rear portion will be capable of swinging upwardly, as will be readily understood.

In the operation of this device when properly installed, as illustrated in Fig. 7, material fed into the threshing machine will be 45 subjected to the usual beating and shaking operation, and as it passes rearwardly, the material will pass beneath the several screen casings in which suction is set up by means of the fan 27 to which rotary motion is imparted. The broken material, such as straw, grain and the like, passing beneath the screen casings in a state of agitation, it is 50 obvious that the lighter substances will rise through the screens 36 and will be carried through the ducts 34, openings 32 and compartment A, beneath the gate or valve 23 and through the fan compartment from 55 which it will be discharged through the duct 20. By the suction set up in the respective screen casings it is true that material such as chaff, bits of straw and the like will be attracted and will be caused to some extent to 60 adhere to the screens and to obstruct the 65 openings therein: it is found, however, that

the material which is constantly passing in a rearward direction through the casing of the threshing machine will exert a 'wiping' action on the under faces of the screens, whereby the latter will be kept sufficiently clean 70 and open for all practical purposes, it being, moreover, notable that the screens will not obstruct the rearward passage of material through the threshing machine, because they will yield in an upward direction when material comes in unusually heavy masses. It may also be stated that owing to the peculiar 75 action of the screens with reference to the material passing through the machine, the preferred construction of the screens is that shown in Fig. 3, each screen being composed of a sheet of metal having narrow elongated slits or slots that will permit the passage 80 only of fine dust and such material as it is desired to eliminate, while bits of straw, chaff and the like will be readily wiped from the faces of the screens.

By the improved device which may be constructed and installed at a very moderate expense, the obnoxious and dangerous dust and gases will be completely eliminated from the straw, thereby avoiding danger of fire to a very large extent.

Another very important advantage is that the straw will be freed from impurities, and thereby rendered more fit for use as animal bedding and the like, while the removal of dust will also prevent vermin from breeding therein.

Having thus described the invention, 100 what is claimed as new, is:—

1. The combination with a conveyer and a casing for said conveyer, of a dust collector and eliminator comprising a housing having two communicating compartments 105 and a gate for varying the area of the opening of communication, one compartment being provided with a plurality of inlets and the other compartment having an outlet, means for setting up an air current in the last mentioned compartment discharging through the outlet, ducts communicating with the inlets of the first mentioned compartment and extending within the casing of the conveyer, and screen casings carried by said ducts.

2. The combination with a conveyer and a casing for said conveyer, of a dust collector and eliminator comprising a housing having two communicating compartments 120 and a gate for varying the area of the opening of communication, one compartment being provided with a plurality of inlets and the other compartment having an outlet, means for setting up an air current in the last mentioned compartment discharging through the outlet, ducts communicating with the inlets of the first mentioned compartment and extending within the casing 125 of the conveyer, and screen casings carried 130

by said ducts, said screen casings comprising each a dome, a screen hingedly connected therewith, and flexible collapsible wall members connecting the screen with the dome.

3. In a device of the class described, the combination with a conveyer and a casing for said conveyer, of a screen casing supported within the same, said screen casing comprising a dome, a downwardly and rearwardly inclined screen hingedly connected therewith, and flexible wall members connecting the screen with the dome, said screen facing forwardly with respect to the conveyer, and means for setting up suction within the screen casing to extract dust and light particles from the material passing over the conveyer.

4. The combination with a threshing machine, of a housing supported on the deck thereof, said housing having an outlet and

a plurality of inlets, a driven blower arranged in the housing for setting up suction through the inlets, a conveyer in the casing of the machine, hoods supported at intervals above the conveyer, ducts connecting said hoods with the inlets of the blower casing, screens flexibly suspended from the hoods and lying in the path of material passing over the conveyer, and flexible walls connecting the free edges of the screens with the hood, whereby the exposed faces of the screens will be wiped by the straw and chaff passing over the conveyer, leaving said screens free for the passage of dust.

In testimony whereof I affix my signature in presence of two witnesses.

BENNIE U. GAAR.
